Edward M. Farnum

UNITED STATES PATENT OFFICE

FUKAOKU WATANABE, OF HOLLYWOOD, CALIFORNIA

ADVERTISING DEVICE

Application filed October 7, 1930. Serial No. 486,978.

This invention relates to improvements in an advertising device, and its objects are to provide elements of simple and efficient construction, capable of motion and driven by the slightest movement of the air or wind, and adapted for displaying advertising matter on both sides thereof, and alternately to the observer.

Another object is to provide a device of the character set forth which is well adapted for use as a toy.

To accomplish these and other objects I provide a base or standard, on which is mounted a freely movable and vertically disposed shaft, carrying elements displaying the advertising matter, and provided with opposed weights whereby the device may be adjusted to a perfect balance for free rotary movement thereof.

20 A practical embodiment of the invention is illustrated in the drawings, wherein:

Figure 1 is a sectional elevation of the device. Fig. 2 is a side elevation of the central shaft. Fig. 3 is a side view with balancing weight with a part of the bow frame shown in section. Fig. 4 is a perspective view of the shield detached from the supporting shaft, and shows a side adapted for carrying the advertising matter. Fig. 5 is a bottom plan 30 view of the advertising shield. Fig. 6 is a detail view of a modified form of the bow frame, adapted for the larger sizes of the device.

Referring in detail to the drawings, a standard 7 having a relatively broad base 8, is provided with a central depression 9, at the top, in which is mounted a vertically disposed central shaft 10, having a pointed metal tip 11 at its lower end, and having the notches 12 therein, adapted to receive the resilient bow member 13. Member 13 has loops 14 and 15 therein, and a central loop 16 adapted to engage with a notch 12 in the central supporting shaft 10. A relatively small wire element 17 is wound around the central shaft and has its extremities 18 wound around and engaging in the loops 15, of bow member 13. The extremities 19, of the bow member, have rectangular sections 20, and curved tips 21. On the rectangular sections 20, I mount the

weights 22, which are slideable to adjust the bow member for balancing thereof. I provide a paper fabric shield 23, adapted to be mounted on the central shaft and bow member, the shield having at the top a central aperture 24 to receive the central shaft, and having suitable pins 25, whereby it is secured to the extremities of the bow member.

In use, the shield 23 is provided with the advertising matter (not shown) printed or otherwise placed on the sides thereof. The shield is then placed upon the bow member 13, with shaft 10 extending through the top aperture 24. The weights are then shifted on the bow member to balance the same. After the device is properly balanced, the slightest movement of the air is sufficient to cause it to turn, thereby alternately exhibiting the sides to the observer.

For large and extra large sizes of the device, I provide the bow member with a modified form, consisting of a central tubular portion, comprising tube 26, with slotted extremities 27, adapted to receive wire members (not shown) similar to the extremities of bow member 13. The tube slots have angular extremities 28 to limit the wire members in position.

From the foregoing description and drawings, it may be seen that I have provided an attractive and efficient advertising device, all made of light weight elements, and capable of being agitated by the slightest movement of the air.

Only one set of weights are shown but the device may have larger, smaller and additional weights, which may be quickly applied to attain balance, or to provide turning effort in accordance with the strength of the wind. The bow member may be adjusted to sizes desired by placing wire element in the upper loops 14 or 15, and by lengthening or shortening the distance between loops. The metal pivot point allows the bow member to turn freely in central socket 9. The device may be quickly dismounted and packed in small space for transportation.

The device is well adapted for use as a moving toy, and may have thereon a shield with attractive colors and pictures.

What is claimed is:

1. The combination with a standard having a recessed top, of a shaft vertically disposed and mounted in said recessed top, and having notches in the upper end thereof, a bow member secured to said shaft, a tie wire wrapped around the central shaft and having its extremities secured to the bow member, a shield adapted to display advertising matter thereon, and mounted on the shaft and bow member, and balancing weights disposed on the extremities of the bow member.
  2. The combination with a standard, of a shaft vertically disposed and independently rotatable and mounted on the standard, a bow member carried by the vertically disposed shaft and secured thereto, a shield adapted to display advertising matter and mounted on the shaft and bow member, means for securing the shield in position, and balancing weights on the outer extremities of the bow member.
  3. The combination with a supporting standard having a recessed top portion, of a shaft vertically disposed and independently rotatable and mounted in said recessed end of the standard, a bow member secured to the shaft, an advertising shield mounted on the bow member and shaft, and means for balancing the shaft and elements carried thereby.
  4. The combination with a supporting standard, of elements mounted thereon and independently rotatable relative thereto, and including a bow member with projecting extremities, balancing weights slideable on the said extremities, and a shield adapted for displaying advertising mounted on the rotatable elements.
  5. The combination with a supporting standard, of independently rotatable elements mounted thereon, means for balancing the rotatable elements, and an advertising shield carried by the rotatable elements.
45. In testimony whereof, I hereunto affix my signature.

FUKAOKU WATANABE.
